TYPE CASTING

Gerald S. Fuller, Schenectady, N. Y.

Application July 12, 1937, Serial No. 153,135

10 Claims.

(Cl. 199—47)

My invention relates to type casting and an improved method of producing the desired form of type casting, and more particularly to such type casting in which the molten metal is cast 5 in a mold with a portion of the metal in contact with matrices to form the desired character or line of characters thereon.

A machine commonly used in this art for making such type castings or slugs is known as a 10 "Ludlow" type casting machine. In this machine, the matrices are composed in a stick, placed in the machine with the character recesses in the matrices presented toward the mold; the matrices are then clamped against the mold, 15 and the molten metal is supplied to the mold so as to form the characters in the matrices on the cast metal with a narrow web portion extending from the bottom portion of the type casting. The slug is withdrawn from the matrices, trimmed 20 along the edge of the web opposite the type face to provide an accurate smooth surface for aligning the type face, as required in composition, and the slug is ejected from the machine. The slug is then ordinarily composed in a galley with other type, such as "Linotype" slugs.

It is frequently desirable to compose these 25 slugs cast in the "Ludlow" machine in a plate by providing a recess or mortise in the plate. The slug obtained from this "Ludlow" machine 30 cannot be used without alteration, because it is the practice to make the plates relatively thin and support them in the galley on a base so that the type face or printing face on the plate is in the same plane as the other type faces of the 35 composition with which the plate is used. In order to utilize the slugs cast in the "Ludlow" machine, it has been the practice to saw off the web portion from the body portion of the slug immediately adjacent the body portion. Great 40 care must be exercised by the workman in sawing off this web portion as any inaccuracy will cause the type face in the final composition to be out of line and thus cause a failure to produce clear characters in the final printing.

An object of my invention is to provide a type 45 casting having one or more characters on the face thereof and a height equal to the distance between the type face and the supporting base used in composition so as to avoid the necessity 50 of machine work or the like in making the type casting.

Another object of my invention is to provide 55 a type casting having a character on the face thereof and an indentation therein in which the type casting is parted from the source of metal used in casting, so as to cast all of the type face and aligning surfaces of the type casting in a finished condition.

A further object of my invention is to provide 60 a method of making the type casting in which

a narrow section on a web of the casting is separated from the body portion within the body portion.

Another object of my invention is to provide 5 convenient arrangement for casting two portions of a type casting in such manner that they can be readily separated, and I accomplish this by utilizing a plate interposed between the portion of the type casting and provided with a restricted opening to facilitate the ready separation of the 10 portions.

A still further object of my invention is to provide a method of breaking apart the portions of a type casting without damaging the type faces.

Further objects and advantages of my invention 15 will become apparent as the following description proceeds, and the features of novelty which characterize my invention will be pointed out with particularity in the claims annexed to and forming a part of the specification. 20

In the drawings, Fig. 1 is a plan view of a stick 25 made in accordance with my invention; Fig. 2 is a bottom plan view of the stick shown in Fig. 1; Fig. 3 is an end view on the line 3—3 of Fig. 1; Fig. 4 is a fragmentary cross-sectional view illustrating how the stick shown in Figs. 1 to 3 inclusive is used in a type casting machine; Fig. 5 is a fragmentary perspective view of a slug or 30 type casting having a plate cast therein in accordance with my invention; Fig. 6 is a transverse sectional view of the construction shown in Fig. 5; Fig. 7 is a transverse sectional view of the type face portion of the type casting or slug having a parting recess in the back thereof with the web portion broken away and removed; Fig. 8 35 is a transverse sectional view of a clamp which I prefer to employ in breaking the web from the body portion of the slug or type casting; and Fig. 9 is a front elevation of the construction shown in Fig. 8. 40

Referring to the drawings, in making type 45 castings in a "Ludlow" machine, a stick is used of the construction shown in Figs. 1 to 4 inclusive. This stick comprises a rectangular frame 10 having inclined parallel side walls 11 extending longitudinally thereof in which the matrices used in composition are placed side by side and clamped together in the stick by a clamping block 12 which is slidably mounted in the stick and adjustable by a knob 13 which is secured by 50 a pin 14 to an adjusting screw 15 threaded in the clamping block.

In order to provide for ready separation of the portion of the type casting formed in the matrices from the portion of the type casting formed 55 in the mold, a relatively thin plate 16 is secured to the bottom of the stick, as viewed in Fig. 1. This plate is provided with a restricted opening terminating within the body portion of the type casting so that the web portion of the type cast- 60

ing can be broken away from the body portion without disturbing the smooth aligning surface on the back or bottom of the body portion. It will be understood that this restricted opening 5 may be formed in any desired manner, but I prefer to utilize an elongated slot 17 extending almost the entire length of the body portion of the type casting. This elongated slot 17 is made to terminate within the body portion of the type 10 casting by forming the metal of the plate 16 about the opening and throughout the length of the opening, so that it is rounded and extends into the body portion of the type casting, as indicated at 18 in Fig. 4.

15 Since the plate 16 is cast in the machine as a unit with the slug or type casting, it is necessary that the dimensions of the plate 16 be such as to pass freely with the slug through the machine during the operations of withdrawing the 20 slugs from the matrices, trimming the bottom edge of the slug, and ejecting the slug from the machine, the matrices and the stick remaining in place on the machine. It is therefore desirable to make the plate 16 so that it will have the desired alignment with respect to the matrices and the mold, and yet be freely removable from the stick during the operations performed before the slug and plate are ejected from the machine. The relation of the stick 10, the plate 16, to the 25 mold cavity 19a of the mold 19, and the relation of the rounded portion of the plate 18 about the elongated slot 17 which extends within the mold cavity 20a of the matrix 20 is clearly shown in Fig. 4. The plate 16 is provided with side 30 flanges 16a along the opposite edges which are parallel and slightly spaced outwardly from the side surfaces 11 on the stick so that the matrix or matrices composed in the stick will not come in contact with the flanges 16a. The height of 35 the flanges 16a is such that when the edges of the flanges are in engagement with the stick the surface 16b of the plate is in contact with the flat faces of the matrices about their character casting recesses 20a. These surfaces 16b are flat, 40 and the lower surface of the plate is also flat and fits in good contact with the top surface 19b of the mold 19. The plate 16 is arranged with one end flush with the end of the stick 10 opposite the adjusting handle 13, and the other end thereof at the block 12, there being no flanges 45 on the opposite ends of the plate 16, so that one end of the plate embraces a rectangular boss 10a at one end of the stick, and the other end thereof embraces the adjustable block 12.

50 In order to maintain the plate 16 in the exact relation required, the stick 10 is provided with an alignment bar 21 having a longitudinal finished face 21a which is parallel to the faces 11 and the center line of the stick; the surface 21a 55 which is carried by the stick also conforms closely to the flange 16a throughout its length. The end of the alignment bar 21 is provided with an aligning shoulder 21b which engages the end of the plate 16 so as to locate the opposite end of the plate flush with the end of the stick. The opposite edge of the plate is resiliently urged into engagement with the aligned surface 21a by a spring 22 attached to a pin 23 which is secured to the stick about midway between the opposite ends 60 of the plate.

65 By this arrangement, the operator can slide the plate 16 into position on the stick along the aligning surface 21a with the edges 16a of the flanges in engagement with the stick. This will 70 force the spring 22 outwardly so as to securely 75

grip the plate against the aligning surface 21a, and the movement of the plate will be arrested by engagement with the shoulder 21b in its final aligned position. It is to be noted that the plate 16 can be very readily pulled away from the stick 5 as required when the slug is trimmed and ejected from the machine.

After the plate 16 is assembled on the stick, the matrices are composed in the stick with their faces in contact with the surface of the plate 16 10 and in engagement with the aligning surfaces 11 of the stick. The matrices are then clamped by the adjusting screw 13. The stick is then placed in the type casting machine in the position shown in Fig. 4, the matrices are clamped against the plate 16 so as to form a joint about the casting recesses in the matrices which will prevent molten metal leaking therefrom when the molten metal is supplied thereto in casting. The lower surface of the plate is at the same time retained in similar close contact with the top surface 19b of the mold 19, and the spacer plate 24 is clamped between the mold 19 and a support 25 from which molten metal is supplied to the type casting. Molten metal is then supplied under pressure 25 and the type casting is formed in the machine. The bottom edge 26a of the type casting 26 is 30 trimmed by suitable knives, and the type casting or slug together with the plate 16 is ejected from the machine in the form shown, for example, in Fig. 5, in which a type casting is shown having a relatively wide body portion 27 on which the characters are cast which is integral with the lower web portion 26. The metal flowing from the web portion 26 to the body portion 27 35 passes through the restricted opening 17 within the finished back surface of the body portion 27. The web portion 26 is then broken away from the body portion 27 by clamping the type face of the body portion 27 securely against a 40 smooth surface, and then fracturing the narrow weakened section of the web portion 26 at the mouth of the opening 17 within the body portion 27, producing the body portion 27 of the configuration shown in Fig. 7. The height between the 45 bottom smooth surface 27b of the type casting shown in Fig. 7 to the upper type face 27a is equal to the distance between the top surface of a base used in a composition in a galley or the like and the plane of the adjacent type face 50 used in the composition which is generally known as plate high or of shell cast height. In this way, I am enabled to readily produce cast characters in a slug of a height which can be used with facility to make various unusual compositions and conveniently change compositions by morticing plates or the like. Furthermore, an operator can readily produce the slugs of the desired height with one or more characters and without the necessity of altering the finished 55 surfaces of the type casting as required by present methods such as sawing and filing, or the like.

Although I have explained my invention in connection with a "Ludlow" type casting machine, it will be apparent to those skilled in the art that other types of machines may be utilized to carry out my invention.

In breaking the body portion 27 from the web portion 26, I provide a breaker, shown in Figs. 70 8 and 9, comprising a frame 30 secured to the edge of support 31 by a bolt 32. A swinging plate 33 is mounted on a bar 34 which is carried by ears 35 attached to the frame. The plate 33 is loosely mounted on the bar 34 by ears 33a, 75

and a cam 36 is arranged in the middle of the bar 34 to be operated by a handle 37. The slug with the attached plate shown in Figs. 5 and 6 is inverted and placed with the type faces in contact with the smooth surfaces of the plate 33, one side of the plate 16 being received beneath a flange 36a on the frame. The handle 37 is moved upwardly so as to cause the cam 37a to securely clamp the type face against the surface 10 of the plate 33, which prevents damaging the type face. A bar 38 is also pivotally mounted on the bar 34 by arms 39a, and a handle 39 is secured to the intermediate portion of the bar 38. The face of the plate 33 is slightly rounded to engage the side of the web of the slug, and a slight pressure exerted on the handle 39 breaks the web from the body portion of the type casting, so that the plate 16 can be very readily separated from the body portion and the web portion, and the body portion 27 can be utilized as above described.

I have described the particular embodiments of my invention and the methods employed in carrying out my invention, I do not desire my invention to be limited to the particular arrangement or method above set forth, and I intend in the appended claims to cover all modifications which do not depart from the spirit and scope of my invention.

What I claim as new and desire to secure by Letters Patent of the United States, is:

1. The method of making a plate high type casting which comprises casting a molten metal in a type casting machine in contact with character recesses in one or more matrices and forming the type casting plate high with a relatively narrow web portion extending from the back thereof, clamping the type face on a supporting surface, and breaking the web portion from the type casting between the type face and the back thereof.

2. The method of making a plate high type casting which comprises forming a casting having a body portion with characters on one face thereof and a relatively narrow web portion extending from the back of the body portion and having a relatively narrower section on the web portion extending within the back of the body portion, clamping the character face against a supporting surface and breaking the narrower web portion from the body portion within the back thereof by applying a force in a direction substantially parallel to the character face.

3. The method of making a type casting which comprises forming a body portion in a matrix and an integral web portion in a mold cooperating with the matrix wherein a thin plate having a narrow slot for admitting metal from the web portion is placed between the matrix and the mold, and separating the web portion from the body portion at the mouth of the narrow slot in said plate and within the back of the body portion.

4. The method of making a type casting which comprises forming a body portion in a matrix and an integral web portion in a mold cooperating with the matrix wherein a thin plate having a restricted opening for admitting metal from the web portion to the body portion is placed between the matrix and the mold and separating the web portion from the body portion at the mouth of the restricted opening in said plate and within the back of the body portion by planting the body portion against a supporting surface and breaking the web portion therefrom.

5. A type casting machine comprising a matrix for forming characters in cast metal, a mold cooperating with the matrix to form at least a part of the body of the type casting, and a plate interposed between the matrix and the mold having a restricted opening through which molten metal can flow from the mold to the matrix, the restricted opening in said plate extending within the back of the metal cast in said matrix to provide for easy separation of the metal cast in the mold from the metal cast in the matrix without any rough surfaces on the back of the type casting formed in the matrix.

6. A plate for use in type casting machines to effect the ready separation of two portions of metal cast in the machine having a restricted opening therethrough adapted to form a passage for molten metal during casting between the two metal portions and extending within the portion on which the type face is cast so as to provide a smooth supporting surface for the type casting and to provide for separation of the two cast portions without roughening of the back surface of the portion having the type faces.

7. In combination with a stick for supporting a series of matrices for casting type in a type casting machine, a plate carried by said stick and having a restricted opening extending within the casting recess in the matrices composed in the stick and a surface adjacent the opening for sealing the faces of the matrices against the leakage of molten metal.

8. In combination with a stick for supporting a series of matrices for casting type in a type casting machine, a plate carried by said stick and having a restricted opening extending within the casting recess in the matrices composed in the stick and a surface adjacent the opening for sealing the faces of the matrices against the leakage of molten metal, and means for removably securing the plate to said stick.

9. In combination with a stick for supporting a series of matrices for casting type in a type casting machine, a plate carried by said stick and having a restricted opening communicating with the casting recess in the matrices composed in the stick and a surface adjacent the opening for sealing the faces of the matrices against leakage of molten metal, said plate having flanges embracing the sides of the matrices extending through the stick and engaging the stick adjacent the matrices, a surface carried by said stick for aligning said flanged plate longitudinally and transversely with respect to said stick, and means for removably securing said plate against the aligning surfaces carried by said stick.

10. In combination with a stick for supporting a series of matrices for casting type in a type casting machine, a plate carried by said stick and having a restricted opening communicating with the casting recess in the matrices composed in the stick and a surface adjacent the opening for sealing the faces of the matrices against leakage of molten metal, said plate having flanges embracing the sides of the matrices extending through the stick and engaging the stick adjacent the matrices, a surface carried by said stick for aligning said flanged plate longitudinally and transversely with respect to said stick, and means for resiliently securing said plate against the aligning surfaces carried by said stick.

GERALD S. FULLER.
